Vanderleeden LLP

(57) **CLAIM**

The ornamental design for a wash sink, as shown and described.

DESCRIPTION

FIG. 1 is a top, front, right side perspective view of a wash sink according to a first embodiment of the present disclosure;

FIG. 2 is a top, front, left side perspective view thereof;

FIG. 3 is a bottom, rear, right side perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and

FIG. 9 is a bottom plan view thereof;

FIG. 10 is a top, front, right side perspective view of a wash sink according to a second embodiment of the present disclosure;

FIG. 11 is a top, front, left side perspective view thereof;

FIG. 12 is a bottom, rear, right side perspective view thereof;

FIG. 13 is a front elevational view thereof;

FIG. 14 is a rear elevational view thereof;

FIG. 15 is a left-side elevational view thereof;

FIG. 16 is a right-side elevational view thereof;

FIG. 17 is a top plan view thereof; and,

FIG. 18 is a bottom plan view thereof.

The broken lines shown in the drawings represent portions of the wash sink and form no part of the claimed design.
